HAIR DRESSING DEVICE

Grey de Boer, New York, N. Y.

Application February 11, 1947, Serial No. 727,776

2 Claims. (Cl. 132—39)

1

This invention relates to improvements in hair dressing devices, more particularly to devices of the type for curling or waving the hair, herein referred to briefly as "hair curlers."

A major disadvantage of hair curlers of conventional design and construction is that they are quite uncomfortable if worn at night. Another disadvantage of many forms of hair curlers is the danger of injury to the wearer due to defects developing in the curler construction after repeated re-use. Such defects generally arise from the fact that the hair curler, in order to stay in place, has to be deformed materially, causing structural elements in it to break.

The invention provides an improved hair curler which is comfortable for night wear, suitable for daytime wear, and which possesses many features and advantages over curlers of known construction.

The various objects, features and advantages of this invention will appear more fully in the detailed description which follows accompanied by drawings showing, for the purpose of illustration, preferred embodiments of the invention.

The invention also consists in certain new and original features of construction hereinafter set forth and claimed. Although the characteristic features of this invention which are believed to be novel will be particularly pointed out in the claims appended hereto, the invention itself, its objects and advantages, and the manner in which it may be carried out may be better understood by referring to the following description taken in connection with the accompanying drawings forming a part of it in which,

Figure 1 is an elevational view of a curler embodying the invention;

Figure 2 is a section taken on line 2—2 of Figure 1;

Figure 3 is a section taken on line 3—3 of Figure 1;

Figures 4 and 5 illustrate modified forms of construction of the end of the curler; and

Figure 6 is an elevational view of a modified form of curler.

In the following description and in the claims, various details will be identified by specific names for convenience. The names, however, are intended to be as generic in their application as the art will permit.

Like reference characters refer to like parts in the several figures of the drawing.

In the drawings accompanying, and forming part of, this specification, certain specific disclosure of the invention is made for the purpose

2

of explanation of broader aspects of the invention, but it is understood that the details may be modified in various respects without departure from the principles of the invention and that the invention may be applied to other structures than the ones shown.

Referring now to the drawings, the hair curler shown in Figures 1, 2, and 3 comprises a flexible flat core 11 covered by a covering 12. The core 11 may be a strip of easily flexible metal such as soft brass or aluminum, may also be a plastic material such as a synthetic resinous composition. It may be solid or be in plies. It may also consist of a plurality of strands lying side by side, suitably interconnected by an adhesive or by braiding so as to form a substantially flat flexible core.

The covering 12 may be a fabric or fibrous structure applied over the core in a suitable manner, for example by a braiding machine. The covering 12 is secured to the core 11 either by frictional contact or by cement applied at appropriate spots as at 13 or over the entire length of the core.

According to the invention, the covering, webbing or netting 12 extends as a substantially open weave 14 beyond the ends of the core 11 for a length sufficient to permit insertion through the ends 14 of the covering, of a hair pin of suitable form wherewith the curler may be secured to the wearer's hair. The density of the extended weave or braiding 14 is such as to permit easy insertion therethrough of a hair pin 16, not only of the conventional wire type, but also preferably of the blunt ended bobby-pin type.

In the use of the curler, a strand of hair is wound on the covered core portion of the curler, the curler is then bent slightly to fit the shape or curvature of the head at the respective place where it is to stay, and is then secured to the hair of the wearer simply by inserting a hair pin through each of the open weave ends 14.

The hair pins hold the curler securely in place and yet do not add to the thickness of the curler, and so that the curler and the few turns of hair wound thereon remains a substantially flat structure which is hardly felt by the wearer and is not uncomfortable for night wear. In distinction, it will be remembered that many conventional forms of hair curlers are either relatively thick, or require bending over of the ends or bending of the entire curler back upon itself so that the wearer, literally speaking, sleeps on pencils at night.

The curler also lends itself admirably to wear

during the daytime as part of a coiffure calling for a roll or rolls. For such use, the curler is preferably made in a color to match the wearer's hair color. The hair may be wound on the curler up to the end or to a point near to the end of the curler which, as is readily seen, does not interfere in any way with the insertion therethrough of hairpins to hold it in place.

The end portions of the curler may be made of a width equal to that of the core as shown in Figure 1 or of reduced width as shown at 14' in Figure 4. The ends may also be of enlarged width as shown at 14'' in Figure 5. The ends of the core 11 may be slightly tapered to facilitate securing of the braiding 12 thereto as shown in Figures 4 and 5.

For purposes where curlers of substantial length are required, it may be desirable to secure the curler to the wearer's hair intermediate its ends. The form of curler shown in Figure 6 has core portions 11' leaving an open space 15 therebetween through which a hairpin may be placed. The open space 15 may be provided either by employing two separate core portions 11' or by providing a single core having an aperture near its center. The center portion 15 has a covering of substantially open braiding through which a hairpin may be placed.

The invention thus provides an improved hair curler which is inexpensive to manufacture and offers many advantages over existing forms of curlers. It has a long life due to the fact that only slight bending of the core is necessary to make it conform to the shape of the head of the wearer and no abrupt bends are required as, for example, in the type of curlers which are held in place by bending back the ends. The improved curler is comfortable for night wear because it lies flat. It may also be worn in comfort without being conspicuous during the daytime. Itcurls the hair well by reason of having sufficient rigidity to permit tight winding of the hair thereon. This is not the case in the conventional type of curlers or rolls consisting of an open braiding in their entirety. The curler will not injure the wearer by protruding sharp ends or sharp edged portions such as occur often in conventional types of curlers after excessive bending and resulting breaking. The improved curler will not catch or pull hair because it is entirely free from interlocking elements provided in many conventional hair curlers for the purpose of locking the ends of the curlers together or holding the curler in place. The absence of interlocking parts offers the further advantage that the curler 55 will not accidentally open, shift, or release the

tightly-wound hair therefrom since the hair pins inserted from the ends hold it securely in place.

Obviously the invention is not restricted to the particular embodiments herein shown and described, but may, with equal advantage, be applied to other forms. Such modifications will readily occur to persons skilled in the art and do not involve departure from the spirit and the essence of the invention.

10. What is claimed is:

1. A hair curler comprising, in combination, a flexible flat core and a braided covering secured thereto, the ends of the covering extending beyond the ends of the core, the portion of the covering extending beyond the core being sufficiently long and having a weave sufficiently open for insertion through said ends of a hair pin, where-with the curler may be secured to the hair of the wearer in substantially flat condition, the core having an open portion intermediate its ends, over which open portion an open weave portion of the said covering extends for insertion of a hair pin therethrough for securing the curler to the wearer's hair intermediate the ends of the curler.

2. A hair curler for forming individual curls of individual locks of hair, the curler comprising, a flat core of dense flexible sheet material of sufficient density to resist penetration by a hair pin and of sufficient stiffness to resist twisting under the tension of a lock of hair wound thereon, and a braided covering on said core and secured thereto, the ends of the covering extending beyond the ends of said core, the portions of the covering extending beyond the core being sufficiently long and having a weave sufficiently open for insertion therethrough of a hair pin for securing the curler to the hair of the wearer in substantially flat condition without bending a portion of the core back upon itself.
